UNITED STATES PATENT OFFICE.

CHARLES E. JONES, OF CHICAGO, ILLINOIS, ASSIGNOR TO METAL ARTS AND CRAFTS CO., OF CHICAGO, ILLINOIS, A CORPORATION OF ILLINOIS.

DESIGN FOR A SANITARY FIXTURE.

45,940.

Specification for Design.

Patented June 16, 1914.

Application filed February 27, 1914. Serial No. 821,580. Term of patent 3½ years.

To all whom it may concern:

Be it known that I, CHARLES E. JONES, a citizen of the United States, residing at Chicago, in the county of Cook and State of Illinois, have invented a new, original, and ornamental Design for a Sanitary Fixture, of which the following is a specification, reference being had to the accompanying drawing, forming a part thereof.

The figure is a side elevation of a sanitary fixture, showing my new design.

I claim:

The ornamental design for a sanitary fixture as shown.

CHARLES E. JONES.
